Patented Jan. 27, 1914.

UNITED STATES PATENT OFFICE.

MARIA HIGGINS, OF LIMESTONE, MAINE.

CHURN.

1,085,337.

Specification of Letters Patent.

Patented Jan. 27, 1914.

Application filed January 9, 1913. Serial No. 741,059.

To all whom it may concern:

Be it known that I, MARIA HIGGINS, a citizen of the United States, residing at Limestone, in the county of Aroostook, State of Maine, have invented certain new and useful Improvements in Churns; and I do hereby declare the following to be a full, clear, and exact description of the invention, such as will enable others skilled in the art to which it appertains to make and use the same.

This invention is directed to improvements in churns, and more particularly to one for whipping cream.

15 The invention has for its object to so construct a device of this character which may be easily clamped upon a suitable support and rapidly rotated so as to thoroughly whip the cream or make butter, as desired.

20 A further object of the invention is to so construct a device of this character that the same may be produced at a minimum cost, and one in which the cover will be positively held in place.

25 With these and other objects in view, this invention resides in the novel features of construction, formation, combinations and arrangements of parts to be hereinafter more fully described, claimed and illustrated in 30 the accompanying drawing, in which:

Figure 1 is a front elevation of the device. Fig. 2 is a side elevation. Fig. 3 is a top plan view. Fig. 4 is a bottom plan view. Fig. 5 is a vertical sectional view. Fig. 6 35 is a sectional view on line 6—6 of Fig. 1.

Referring to the drawing the numeral 1 designates a frame consisting of a base 2 having rising from the opposite sides thereof spaced standards 3, said base being adapted 40 to be secured to the edge of a table or the like by a suitable clamp 4.

The churn body 5 is formed from glass, of if desired the same may be made from enameled ware. The churn body 5 is in the form 45 of a glass jar and is closed by a top 6, said top being held in place by the bail 7, said bail being secured to the neck of the body by the band of wire 8. Pivots connected to the band 8 are the links 9 having formed thereon eyes 10, said eyes terminating in the curved lever 11, and as the lower ends 50 of the bail 7 are pivotally connected in the eyes 10, the lever when pressed downwardly will cause the bail 7 to tightly engage the top 6 to hold the same in place.

A body receiving frame 12 is provided

and consists of a sheet metal band 13 having formed upon its sides at diametrically opposite points trunnions 14, which engage in the notches 15 formed in the upper ends 60 of the standards 3, one of said trunnions terminating in a crank handle 16. The frame 12 further consists of a pair of loops 17, the upper ends of which are secured to the lower edge of the band 13, said loops 65 having their bight portions arranged in crosswise relation so that the bottom of the body 5 will rest thereon when the same has been passed through the band 13.

Having their lower ends secured to the 70 band 13 and at points diametrically opposite are arms 18 and 19, the latter being somewhat longer than the former. To the upper end of the arm 18 is connected a clasp 20, a similar clasp being connected to the 75 upper end of the arm 19.

Pivots connected centrally of the lever 11 is a yoke 22, a similar yoke 23 being connected to the wire band 8.

After the desired amount of cream has 80 been placed in the body 5 the top 6 is placed thereon and held firmly by the bail 7 upon forcing the lever 11 against the breast of the body, whereupon the clasp 20 carried by the short arm 18 engages the 85 yoke 22, and the clasp 21 upon the arm 19 engages the yoke 23 carried by the band 8, thus firmly holding the body in the frame and the top 6 against accidental removal. Thus it will be seen that upon gripping 90 the crank handle 16 and turning the same the frame 12 will be rapidly rotated and thus the body 5.

It is of course obvious that a rubber gasket is placed between the jar neck and cap 95 6 to insure a liquid tight joint.

What is claimed is:—

A device of the class described comprising a frame consisting of a base having a pair of spaced standards mounted thereon, 100 means for clamping the frame to a support, slots formed in the upper ends of the standards, a body receiving frame consisting of a band having trunnions connected thereto and adapted to engage said slots, a 105 pair of loops having their upper ends connected to the band and their bight portions arranged in crosswise relation, a body adapted to be inserted in the band so that its bottom will rest upon the bight portions 110 of said loops, arms secured to the band, a top for the body, a ring carried by the

body, a bail pivotally connected to the ring and having a curved lever, yokes carried by the bail and ring, said yokes being engaged by the clamps carried by the arms to hold the body in said body receiving frame, a top upon the body and means for rotating said frame and thus the body.

In testimony whereof, I affix my signature, in the presence of two witnesses.

MRS. MARIA HIGGINS.

Witnesses:

AUBREY C. FROST,
PERCY E. HIGGINS.
